UNITED STATES PATENT OFFICE.

HUBERT F. KRANTZ, OF BROOKLYN, NEW YORK, ASSIGNOR TO KRANTZ MANUFACTURING COMPANY, INC., OF BROOKLYN, NEW YORK, A CORPORATION OF NEW YORK.

SAFETY-SWITCH-OPERATING DEVICE.

1,399,494.

Specification of Letters Patent.

Patented Dec. 6, 1921.

Application filed August 2, 1917. Serial No. 184,010.

To all whom it may concern:

Be it known that I, HUBERT F. KRANTZ, residing at Brooklyn, in the county of Kings and State of New York, have invented certain new and useful Improvements in a Safety-Switch-Operating Device, of which the following is a specification.

This invention relates to a safety switch operating device.

10 A particular object of the invention is to provide a simple, practical, and thoroughly efficient means for guarding against likelihood of the switch being left in the "on" position at a time when it should be in the 15 "off" position.

A further object is to provide a switch with an operating member which may be readily attached and removed at will, and which when removed leaves the switch necessarily in the "off" position and the parts so guarded as to prevent likelihood of the switch being moved from "off" position except by the attachment of the operating member.

25 This device has been developed particularly for use in connection with mine works and the like, but it will be apparent that the device may be as readily and as efficiently employed in other connections whenever desired.

30 Other objects and aims of the invention, more or less specific than those referred to above, will be in part obvious and in part pointed out in the course of the following 35 description of the elements, combinations, arrangements of parts and applications of principles, constituting the invention, and the scope of protection contemplated will be indicated in the appended claims.

40 In the accompanying drawings which are to be taken as a part of this specification, and in which I have shown merely a preferred form of embodiment of the invention:

45 Figure 1 is a side elevational view of a switch box, with parts shown in section to disclose a feature of this invention.

Fig. 2 is a top plan view of the structure shown in Fig. 1, and

50 Fig. 3 is a transverse sectional view taken substantially upon the plane of line III of Fig. 1.

55 Referring to the drawings for describing in detail the structure which is illustrated therein, the reference character L indicates

the switch box. This may be of any size, shape or form and of any suitable material to contain and protect the switch mechanism G. In fact, in some instances, the switch box might be omitted if desired. 60

The switch mechanism G illustrated, includes a blade 1 which is pivotally mounted as at 2, to swing into and out of electrical engagement with a pair of co-operative contacts 3 and 4 for controlling passage of current through the box.

The switch mechanism is similar in its general construction to that illustrated in my pending application Serial No. 85,852 filed March 22, 1916, and its operations may 70 be controlled by the oscillating movement of a plate 5 which is pivotally mounted as at 6, to swing into "on" and "off" positions.

The operating member, or handle H, is formed as a separate and independent member and may be connected to and removed from the switch mechanism at will. At its inner end it is provided with a pair of legs 7 which are spaced apart to receive a portion of the plate 5 between them when the handle is inserted into operating position, as shown in Fig. 3 and by the full lines in Fig. 1. Each of the legs 7 is formed with a slot 8 longitudinally thereof and opening through the ends of said legs and these slots 85 engage over a suitable lug, or lugs, 9 projecting laterally from the opposite sides of the plate 5. Preferably two lugs are employed at each side of the plate, and these are spaced apart as shown so as to constitute in effect an elongated member for engaging within the slots 8. By this arrangement the handle may be readily connected to the plate 5 to swing the plate by means of the handle. 95

In order to prevent disengagement of the handle from the plate at all times except when the plate is in the "off" position, a semi-circular housing 10 is arranged adjacent the plate, this housing having a slot 100 11 formed through its arcuate wall 12 to receive the operating handle. The operating handle is formed with a reduced portion 13 of a size to move readily in the slot. It is also provided with a pair of shoulders 105 14 at the junction between the reduced portion 13 and the legs 7 and these shoulders ride beneath relatively over-hanging portions 15 of the housing at all times except when the plate 5 is in the "off" position. 110

When the plate 5 is in the "off" position the shoulders 14 register with an enlarged opening 16 formed in the housing by cutting away a portion of the over-hanging parts 5 15 so that the handle may be withdrawn. The shoulders 14 riding beneath the parts 15 positively prevent the withdrawal of the handle except when it registers with the opening 16.

- 10 In employing this device in connection, for instance, with mine work, the device is arranged at a convenient locality, either at the entrance to the mine, or at the entrance to a given portion of the mine. The miner obtains 15 the operating handle, which may be numbered to identify it with a given switch box, from a main office. He then proceeds to the switch box, inserts the handle and moves the switch to "on" position. It is an 20 established rule that he must return the handle when he leaves the mine. Hence he must necessarily swing the handle into the "off" position in order to return it. Thus the current which he required for lights or 25 other purposes during his presence in the mine is necessarily shut off when he leaves.

It will of course be understood that whenever desired the relativities as to size and proportions of the parts of the operating 30 handle with respect to the parts of the switch mechanism with which they coöperate may be such as to render a given switch inoperative except by means of a given handle.

As many changes could be made in this 35 construction without departing from the scope of the invention as defined in the following claims, it is intended that all matter contained in the above description or shown in the accompanying drawings, shall be interpreted as illustrative only and not in a limiting sense.

Having thus described my invention, what I claim as new and desire to secure by Letters Patent is:—

- 45 1. A safety switch operating device comprising a box, a switch mechanism within the box having a part pivoted to swing into "on" and "off" positions, an operating handle having legs to straddle said part and 50 having means to otherwise engage said part to swing said part by said handle and to permit disconnection of said handle from said part, a guard member arranged to guard said part, said guard member having an 55 arcuate wall formed with a slot therethrough to accommodate movements of the operating handle, the operating handle having a relatively enlarged inner end portion and a relatively reduced portion adjacent the rela-

tively enlarged portion providing a shoulder 60 upon the operating member, the slot being of a width to accommodate the relatively reduced portion and to provide an overhanging part disposed to be engaged by the shoulder of the operating handle to prevent 65 detachment of the operating handle, and the slot being enlarged at one end to permit passage of the shoulder and detachment of the operating handle when the part is in the "off" position. 70

2. A safety switch operating device comprising a switch member having a part movable into "on" and "off" positions, a separately formed manually operable member for moving said part, a guard member for 75 said part, said manually operable member having a relatively enlarged end portion adapted for detachable engagement with said movable switch part, said manually operable member also having a relatively 80 reduced portion adjacent the relatively enlarged portion providing a shoulder upon said manually movable member, said guard member having a portion standing to engage the relatively enlarged portion for preventing engagement of the manually operable member with said movable switch part except when said movable switch part is in the "off" position, and the relatively reduced portion of the manually operable member 90 being disposed to accommodate the mentioned portion of the guard member above said shoulder when the movable switch member is in other than the "off" position. 85

3. In a switch mechanism comprising a 95 box, a switch blade therein, and a pivotally mounted operating element for said switch blade, projecting outwardly through an opening in one wall of said box, the combination therewith of a guard member fixed to 100 the mentioned wall of the box in a position substantially inclosing the projecting portion of said operating element, a separate handle having a part adapted to be inserted through an opening in said guard member 105 and into functional relation with said operating element, and said guard member and said handle having parts coöperative to prevent the handle from being connected to or disconnected from said operating element 110 except when said operating element is in a given position of pivotal movement.

In testimony whereof I affix my signature in the presence of two witnesses.

HUBERT F. KRANTZ.
